US0D1006627S

(12) **United States Design Patent** (10) **Patent No.:** **US D1,006,627 S**
(45) **Date of Patent:** **** Dec. 5, 2023**

(54) **PACKAGING CONTAINER**

(71) Applicant: **Method Products, PBC**, San Francisco, CA (US)

(72) Inventor: **Louis Filosa**, San Francisco, CA (US)

(73) Assignee: **Method Products, PBC**, San Francisco, CA (US)

(**) Term: **15 Years**

(21) Appl. No.: **29/892,900**

(22) Filed: **May 23, 2023**

Related U.S. Application Data

(63) Continuation of application No. 29/802,344, filed on Aug. 4, 2021, now Pat. No. Des. 991,038.

(51) **LOC (14) Cl.** **09-03**

(52) **U.S. Cl.**

USPC **D9/432**; D3/294; D9/423; D9/522

(58) **Field of Classification Search**

USPC D9/522, 530, 542, 560, 565, 420, 424, D9/432, 499, 423; D3/201, 273, 294

CPC A45D 40/00; A45D 2040/0012

See application file for complete search history.

(57) **CLAIM**

The ornamental design for a packaging container, as shown and described.

DESCRIPTION

FIG. 1 is a top perspective view of a packaging container showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a packaging container showing the claimed design;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The shade lines in the figures show contour and not surface ornamentation.

1 Claim, 16 Drawing Sheets
